COLLAPSIBLE SCAFFOLD

Fred Hartmann, St. Louis, Mo.

Application October 8, 1945, Serial No. 620,907

1 Claim. (Cl. 304—2)

1

My invention has relation to improvements in scaffolds and it consists in the novel features of construction more fully set forth in the claim.

The principal object of my invention is to provide a scaffold that is adjustable as to width to facilitate working in narrow places, and also permit movement through doorways from room to room without disassembly. A further object of the invention is to embody in the construction features of adjustment whereby the platform may be positioned for ceiling heights between eight and fifteen feet. The scaffold may also be knocked down and collapsed within very narrow compass for transporting the same from job to job.

Other advantages of my invention will be better apparent from a detailed description in connection with the accompanying drawings, in which—

Figure 1 is a side elevation of my improved scaffold set up for use; Fig. 2 is an end elevation thereof; Fig. 3 is a plan view of one end only of the scaffold; Fig. 4 is a plan similar to Fig. 3 except that the scaffold has been contracted to a narrower width than shown in Fig. 3; Fig. 5 is an enlarged cross-section on the line 5—5 of one of the standards with the end frame shown dotted in a second position; Fig. 6 is an enlarged end elevation (with parts broken away) of one of the standards together with a portion of an end frame and supporting mechanism for the platform (not shown); Fig. 7 is a side elevation of the parts shown in Fig. 6 from the inside; Fig. 8 is an enlarged outside elevation of the standard shown in Figs. 6 and 7; Fig. 9 is a cross-sectional detail taken on a plane indicated by the line 9—9 of Fig. 6; Fig. 10 is a cross-sectional detail taken on the line 10—10 of Fig. 1; and Fig. 11 is a side elevation of an extension member (showing other parts dotted) whereby the standards may be increased in height.

Referring to the drawings S,S,S,S represent four standards which serve to support the platform P made up of stringers 1, 1 and floor boards 2. The standards S,S at each end are connected by end frames F made up of sections 3 and 4 connected together by hinges 5, 5 along a central parting line X. The frame section 3 is connected to one standard S by hinges 6, 6 and frame section 4 is connected to the other standard S by hinges 7, 7.

Each of the standards S is U-shaped in cross-section (Fig. 5) and has inwardly turned flanges 8, 8 to provide a slot 9 on its inner face for a purpose presently to appear. Each standard S also has a bottom plate 10 welded to it to which

2

is secured a caster 11. A set screw 12 is threaded into caster housing 13 so that the roller may be locked against rotation when desired. The inner rail 14 of frame section 3 is extended downwardly and carries a caster 15 on its lower end to give rolling support to end frame F at its parting line X. From what has thus far been described it is apparent that the four standards are adjustably connected by end frames F, F, so that the end standards (or either pair) may be moved to and from each other to either diminish or increase the scaffold width.

Obviously, the frame sections 3 and 4 should be locked in their several adjusted positions. I accomplish this by the use of a plurality of brace bars such as bar 16 which is perforated to fit over studs 17, 18 projecting upwardly from upper cross-members 19, 20 of frame sections 3 and 4 when the frame sections are in line to provide maximum width of the scaffold. When the frame sections 3 and 4 are broken inwardly (Figure 4) the hinge elements 21 and 22 of sections 3 and 4 are brought into line, and studs 23 and 24 projecting from the respective sections may be connected by a bar 25 and secured in place by wing-nuts 26. At this time the scaffold has been contracted to a narrower width. When it is desired to contract the scaffold to a still greater extent, the sections 3 and 4 are secured by brace bars shorter than the bar 16 and perforated to receive studs 17 or 18 spaced the required amount. Obviously there may be any number of such bars.

It will be noted that the extremities 19' and 20' of frame sections 3 and 4 are bent outwardly at an angle of approximately 135 degrees from the plane in which the sections lie so that with the hinge members 6 and 7 an offset angle is formed to permit clearance for the stringers 1, 1 as they are adjusted vertically, as will presently appear. The manner of supporting the stringers will now be described reference being had particularly to Figs. 6 to 9 inclusive.

On the outer side face of each standard S is welded (or otherwise secured) a channel 27 having a plurality of notches 28 spaced along its flanges, and disposed within each standard S is a channel bar 29 of substantial length. The flanges 30, 30 of bar 29 are held in frictional contact with the inner surface of the standard on both sides of flanges 8, 8 by studs 31, 31, 31, 31 which pass through the bar 29 and slot 9 of the standard. The two lower studs 31, 31 are secured directly against the standard S by washers 32 and wing-nuts 33, while the two upper

studs 31, 31 are also utilized to hold a hanger 34 and retaining member 35 against the inner face of the standard. The hanger 34 is generally U-shaped with a depending flange 36 and is held against the standard by the studs 31, 31 which pass through the flange 36 and side 34' of the hanger, said studs being secured by the washers 32 and wing-nuts 33. The retaining member 35 is Z-shaped, one flange 37 of which is secured to the standard by the top bolt 31 and the other flange 38 embracing the hanger to retain its free side 34'' in place. The hanger 34 has an enlargement 39 formed between its bottom 40 and flange 36 in which is an opening 41 to receive a retaining clip 42 which has laterally disposed extremities 43 and 44, the former being lodged in opening 41 and the latter being adapted to fit into any of the pairs of notches 28 formed on the channel 21 whereby the hanger 34 is firmly supported in its adjusted position.

From the foregoing it is apparent that the hangers 34 may be adjusted to any desired horizontal position by loosening the wing-nuts 33 after removing clip 42. The clip 42 is then inserted in its re-adjusted position and the wing-nuts tightened.

The stringers 1, 1 are secured in the hangers 34 by screw-eyes 45. The standards S, S are braced longitudinally by brace bars 46, 46 (Fig. 1) secured by bolts 47 and wing-nuts 48 to the outer face of each standard and pivotally secured to straps 49 hooked over the stringers 1 and secured to them by set screws 50 (Fig. 10).

I have provided extenstions 51 (Fig. 11) for each standard S constructed similarly to the standards except that a tongue 52 extends from the lower end of each extension for entering the upper end of the standard.

When the extenstions 51 are used, it may be desirable to tie the stringers together. This may be accomplished by connecting opposite screw-eyes 45 together by a chain 53.

It should be obvious from the above description that my improved scaffold may be folded together to facilitate its removal from one room to another without completely dismantling it.

Having described my invention, I claim:

10 A scaffold having collapsible end frames, said end frames including supporting standards, each of said standards comprising a hollow slotted member having a notched bar on its outer face, a hanger assembly operable in said slot, means for clamping the assembly to the standard, and means for anchoring said hanger assembly to said notched bar.

FRED HARTMANN.
